Claims priority, application Germany, Mar. 9, 1960, 27,541

3 Claims. (Cl. 66—145)

The present invention relates to a thread clamping device, and more particularly to a combined suction and clamping device for securing thread during knitting operations in circular knitting and straight bar knitting machines.

Various thread clamping devices are known, which are generally used in connection with mechanical or electrical cutting devices for separating the threads from the articles being knitted at the end of a course of knitting (see U.S. Patents 2,908,154 and 2,924,958). The cutting device is normally placed at a point in the thread path between the article being knitted and the clamp device which serves to hold the thread end after cutting. The clamping device is positioned in the vicinity of the thread guide or feed means at the point in the knitting where the clamping and cutting is to take place. In particular, circular knitting machines cannot readily accommodate clamping and cutting devices for the knitting thread or yarn since such knitting machines are provided with cylinders of comparatively small diameters wherein several knitting systems or stations are utilized for producing, for example, fine seamless hose. Moreover, it will be appreciated that in the usual straight bar knitting machines, space for accommodating said clamping and cutting devices is very limited as well (see U.S. Patents 2,844,016 and 2,863,310).

It is conventional to provide a suction pipe or nozzle for drawing off the thread ends by suitable suction upon the cutting of the thread at the end of a course of knitting. The suction pipe is generally positioned between the cutting device and the clamping device. Nevertheless, because of the relatively small distance between the suction pipe nozzle and the cutting device, which is made necessary by the lack of sufficient space in the machine, the resulting thread ends upon cutting of the same by the cutting device are so short and stiff that they cannot be readily retained with any degree of efficiency by the air current generated by the suction pipe. Additionally, as is the case where electrical cutting or separating means are employed, such as for the cutting of synthetic or thermoplastic thread or yarn, the heating element, i.e. an electrical resistance wire, is strongly cooled due to the continuous air current of the suction pipe positioned so closely thereto. Naturally, the greatest cooling effect is noticed at the outermost portion of the heated resistance wire or element, which in any case is much harder to keep heated to the desired temperature than would be the remainder of the electrically heated resistance wire or electrical separator means.

It is an object of the present invention to overcome the foregoing drawbacks and to provide an apparatus for the efficient, clamping of the thread used in circular knitting and straight bar knitting machines, such device being utilizable together with a cutting device.

Other and further objects of the invention will become apparent from a study of the within specification and accompanying drawings in which,

FIGURE 1 is a schematic partial perspective view of a portion of a circular knitting machine of conventional design illustrating the position relationship of the thread

2

guide, cutting element, and thread clamping device of the invention,

FIGURE 2 illustrates schematically a partial perspective view of a straight bar knitting machine of conventional design provided with a cutting element, thread guide, and alternate embodiment of the thread clamping device of the invention,

FIGURE 3 illustrates a schematic partial sectional view of a thread clamping device in accordance with the invention similar to that shown in FIGURE 2 containing a modification for looping the thread retained by the device of the invention,

FIGURE 4 illustrates a schematic partial sectional view of the top portion of the thread clamping device of the invention as illustrated in FIGURE 3, and

FIGURES 5 and 6 are further schematic perspective views illustrating the withdrawing and inserting of the thread guide out of and into active feeding position.

In accordance with the present invention, it has been found that a thread clamping device for securing thread ends during knitting operations in circular knitting and straight bar knitting machines may be provided which comprises suction nozzle means and thread engaging surface means arranged in the path of the knitting thread for relative movement from a position out of thread clamping contact to a position into thread clamping contact with one another.

The suction nozzle means preferably includes, in accordance with one embodiment of the invention, used in connection with a circular knitting machine of the dial type, a tubular suction nozzle member positioned in spaced relation to and completely out of contact with the dial cap and a tubular extension member, such members being concentrically positioned for telescopic movement with respect to one another. In this manner, the extension member may be extended into and withdrawn out of clamping contact with the surface means. Conveniently, the extension member outwardly encloses and is axially slidably upon the nozzle member, and the extension member is preferably provided with an elastic end rim for engaging thread when such rim is extended into clamping contact with the surface means. The extension member, for efficient operation, is normally resiliently urged into extended position for suitable thread clamping contact. The urging may be effected by means of a loaded coil spring disposed about the nozzle member and secured thereto at one end, the other end of the spring abutting the extension member for forcing the same into thread clamping contact with the surface means.

To actuate the extension member, for axial movement into and out of thread clamping contact, a draw rod may be connected to the extension member at one end and coupled with a suitable pattern device at the other end which causes the desired actuation to take place during the knitting operation.

A suitable pattern device, for example, may take the form of a guide cam ring concentrically disposed with respect to the cylinder, as will be more fully appreciated from copending U.S. application Serial No. 42,355, filed July 12, 1960, wherein a contact ring or guide cam ring for the control of thread guides is mounted for limited rotational movement in response to a cam drum or pattern drum linkage, such as that shown in British Patent No. 810,225. With respect to the instant case, such guide cam ring may be provided with an upper cam surface thereon which is followed by a follower portion of the draw-rod. Upon suitable actuation of the guide cam ring, the draw-rod will be axially displaced for movement of the extension member into and out of clamping contact with the surface means. If desired, the pattern device may be provided for axially displacing the draw-rod once during each cylinder rotation, as for example

would be the case in the knitting of a reinforcement thread into a reinforcement portion of the hose or tubular fabric article being knitted. One construction of actuation means for axially displacing the draw-rod once for each cylinder revolution is described in detail in copending U.S. application filed simultaneously herewith, Serial No. 93,804, filed March 6, 1961, entitled Thread Changing Apparatus. Of course, the pattern device instead may include a simple pattern drum which rotates at the same rate as the circular knitting machine, in connection with which the device may be used, such that clamping contact will be made once during each cylinder revolution. Various control cam devices of the foregoing type are well known and are indicated, for example, in U.S. Patent No. 2,908,154 and British Patent No. 810,225.

On the other hand, where used with a straight bar knitting machine, a suitable timing device may actuate the clamping means into and out of clamping engagement as for example when the yarn or thread being knitted is removed from knitting action at the end of the last knitting course to be knitted therewith, such as where the thread guide reaches the end of the needle bed. The thread extending between the last stitched loop of the fabric and the thread guide is severed at this time and the end of the thread passing from the thread guide remains secured by the clamping means (see U.S. Patent No. 2,863,310).

Suitably, the suction nozzle means are arranged adjacent the thread guide of the machine at the point where thread clamping is to take place, and a thread cutting element is disposed adjacent the suction nozzle means for cutting the thread for example after thread clamping contact has been achieved between the suction nozzle means and the thread engaging surface means.

Where the thread clamping device is used in connection with a circular knitting machine, the thread engaging surface means is conveniently defined by the top surface of the stationary dial cap so that clamping contact is effected by moving the extension member from withdrawn or opened position into contact with the top surface of such dial cap, i.e. to closed position. In this connection, a thread cutting element is preferably positioned on the dial cap and the thread guide is positioned adjacent the dial cap at the point where thread cutting is to take place. The tubular extension member is thus positioned between the thread guide and cutting element for extension into clamping contact with the dial cap. This occurs where the path of the thread being knitted by the machine is situated intermediate the withdrawn tubular extension member and the dial cap so as to permit the desired clamping.

Alternatively, and especially where the device of the invention is used in connection with straight bar knitting machines, the thread engaging surface means is defined as a cover surface adapted to seal off the suction nozzle means when thread clamping contact is achieved. In this instance, the suction nozzle means need not be provided with a tubular extension, but instead contact is achieved by pivotal movement of the cover surface into clamping engagement with the end rim or edge of the suction nozzle means. Suitably, the cover surface is provided with an elastic portion disposed thereon for achieving sealing engagement with the suction nozzle means while clamping thread therebetween.

In accordance with a preferred modification of the invention, the cover surface is provided with a thread engaging projection means insertable into the suction nozzle means passage during the thread clamping contact. The projection means is adapted to engage the thread to be clamped, and in this manner carry a portion thereof into the suction nozzle means passage upon the thread clamping contact so as to form a loop portion in the thread.

As is specifically the case with straight bar knitting machines of conventional design having a bed of knitting elements, the suction nozzle means may be stationarily positioned at the end of the bed with a thread cutting element disposed adjacent the cover surface between the end of the bed and the suction nozzle means. Suitably, the cutting element and cover surface are mounted on a shaft for movement across the path of the thread to be clamped. These elements are aligned at the end of the bed so that they will be first actuated away from the thread path before the thread guide carrying the thread therealong passes to inactive knitting position. Once the thread or yarn has passed, the shaft is next actuated back across the thread path. Since the cover surface is positioned more forward than the cutting element, the cover surface will engage the thread and move the same into thread clamping contact with the suction nozzle means before the thread will be cut by the cutting element.

An electrical resistance wire heating element of conventional design is normally used for effecting the cutting of the thread after clamping has been achieved. (See U.S. Patents 2,844,016 and 2,863,310.)

It is apparent therefore that in accordance with the present invention, the clamping of the thread is carried out by the opening or rim end of the suction nozzle means together with a thread engaging surface means movable into thread clamping relation therewith. Because of the advantageous covering over of the suction nozzle means during clamping, no cooling air current will flow which would otherwise undesirably cool the electrical resistance wire cutting element. Not only is the avoidance of unnecessary cooling of the electrical cutting element attained but also a saving in the generation of suction through the nozzle means passage. Moreover, the interruption of the suction air current during thread clamping contact may result in the need for less expensive suction equipment or the application of present equipment for a greater number of suction nozzle means.

The elastic material suitably provided on at least one of the thread clamping members for engaging the thread to be clamped, may be in the form of rubber, resilient or soft synthetic, plastic, or other resilient or soft material permitting a sure grasp of the thread and a suitable sealing off of the air current passing through the suction nozzle means.

Naturally, where the thread engaging projection means insertable within the suction nozzle means is present, long thread ends may be retained by the suction nozzle means of the thread clamping device even where the operative elements have been withdrawn from thread clamping contact. Because a long thread end is present as compared with the diameter of the opening of the nozzle means, the thread end will be reliably held by suction when clamping contact ceases. Advantageously, this feature is provided even though the thread separator or electrical resistance wire cutting means is relatively closely positioned to the thread clamping means of the invention as is particularly the case with straight bar knitting machines.

It will be particularly appreciated that the present invention represents an improvement in circular knitting machines having means for forming knitted pattern areas in a tubular fabric, for example, such machine including a needle cylinder, needles disposed in said cylinder, elements cooperating with the needles for formation of stitches, cams for effecting needle movement, yarn feeding or guide means movable from an active yarn feeding position wherein yarn is fed to the needles for knitting thereby to an inactive yarn feeding position wherein the yarn is in non-knitting position, and means for clamping and cutting the yarn when the yarn feeding means is in active yarn feeding position and for releasing the yarn when the yarn feeding means is moved to active

yarn feeding position. The improvement of the invention generally comprises a combined thread clamping and suction device including suction nozzle means and thread engaging surface means which are arranged for relative movement from a position out of thread clamping contact to a position into thread clamping contact with respect to one another when the yarn feeding means or thread guide is in active yarn feeding position. The thread clamping device of the invention, of course, is readily usable together with a closely positioned thread separating or cutting device, since the improvement of the invention is directed to the more efficient clamping and cutting of thread in relatively confined spaces than could be achieved heretofore.

With respect to the drawings, FIGURE 1 shows a portion of a conventional circular knitting machine having a cylinder rotating in the direction of the arrow P, said cylinder being provided with a needle bed having a plurality of needles N axially disposed in slots therein in the conventional manner.

As is customary in circular knitting machines for the production of seamless fine hose, the cylinder is provided with the normal dial 6' for the slidable reception of the transfer bits (one of which is schematically shown at 6''), dial 6' being positioned over the top end of the cylinder. Disposed above the dial 6' is a dial cap 6 which is stationary. Dial cap 6 is provided with a thread separator 5 which may be an electrical resistance wire doubled back on itself to form a vertical heating element maintained at a temperature sufficient to sever the particular yarn or thread used, i.e. nylon, etc.

Disposed immediately above dial cap 6 in spaced relation thereto and completely out of contact therewith is tubular suction member 1 connected with a vacuum or other source of suction remote from the circular knitting machine. Extension piece 2 is telescopically slidable on suction nozzle member 1 and is normally urged in downward direction by coil spring 3 attached at its upper end to suction nozzle 1 by means of a collar 4 and positioned in urging abutment with the top edge of extension piece 2. Extension piece 2 is suitably provided along its lower edge or rim portion with an elastic covering 21 made of rubber, for example, which forms the surface against which the thread F will be secured. Draw rod 7 controls the axial movement of extension piece 2 with respect to suction nozzle 1 so that the extension piece 2 may be urged by spring 3 into thread clamping engagement with the top surface of stationary dial cap 6. Drawrod 7 may be suitably connected with a pattern device such as a pattern drum D rotating at the same rate as the cylinder or any other control means as aforesaid so as to cause displacement of draw-rod 7, as for example, once during each rotation of the cylinder.

In this way, where the needles are suitably actuated in the usual way, by cam means within a certain portion of the circumference of the cylinder as may be the case, for example, in adding a reinforcement thread or yarn to be knitted along only a portion of the knitted article, such as is the case with reinforced soles and heels of fine hose, the thread guide or thread feeding means 8 may be lowered into active position immediately adjacent the needles N in any suitable manner, such as by rotating cam E or by the afore-described means set forth in said co-pending U.S. application Serial No. 42,355. The first needle of that portion of the cylinder needles to be actuated, as by suitable activating cam means, for the knitting of the reinforcement portion of the hose, therefore, will be raised into the path of thread F since thread guide 8 has been downwardly displaced into active knitting feed position across the needle path. The thread F may now be knitted in the normal manner until the knitting course reaches the last needle of that portion of the needles of the cylinder used to knit the reinforcement portion of the hose. When this occurs, thread guide 8 will be suitably upwardly displaced out of active thread

feeding position by suitable control means as aforesaid, whereupon the last needle N of the said portion will remain in engagement with the thread F and carry the same in the direction of the arrow P around the cylinder therewith. When the last needle N passes a certain point, the thread F will be disposed along dial cap 6 directly beneath extension piece 2, extension piece 2 having been upwardly displaced in the meanwhile to permit the thread F to pass directly therebeneath, for example at about 10 the same time that thread guide 8 is upwardly displaced out of active knitting position. Then, extension piece 2 is once more downwardly urged into thread clamping contact with dial cap 6 retaining the thread F securely. At this time, as the said last needle N passes around the 15 cylinder circumference, the thread will abut the then electrically energized thread separator 5 whereupon the thread will be severed leaving only a small end in the reinforcement portion of the hose being knitted, yet leaving a suitably long end portion of the thread F which 20 will be effectively retained by the thread clamping means and especially by extension piece 2, even after the same is next raised from thread clamping contact, due to the suction provided upon raising.

It will be appreciated that during knitting operations, 25 normally extension piece 2 will remain in abutment with dial cap 6 to prevent the undesired passage of suction air current upwardly through extension piece 2 and suction nozzle member 1. The undesired cooling of electrical resistance wire heating element 5 will, therefore, be 30 prevented.

Thus, where the first needle of the needles to be used for knitting the reinforcement portion of the hose comes into engagement with the activating cam means therefor, which may be stationarily positioned while the cylinder 35 containing the needles rotates therewith, suitable pre-selected needle butts on these needles will be urged by the cam means in upward direction just after the thread guide 8 has been downwardly displaced. Stated another way, the thread guide 8 will have been switched to activated 40 position just prior to the passage of the first reinforcement needle therewith. The extension piece 2 remains in clamping engagement with dial cap 6 during this time. Of course, suitable pattern devices may be used to control the timing of the lowering and raising of thread guide 8 into 45 and out of active knitting position which may be carried out in accordance with the aforesaid cam ring displacement arrangement disclosed in said co-pending U.S. application Serial No. 42,355.

Specifically, a pattern drum may be operatively connected by suitable linkage means to actuate cam ring 50 means for lowering and raising thread guide 8, which drum revolves in dependence upon the rate of revolution of the knitting cylinder or independent thereof as the case may be. Consequently, thread guide 8 will be inserted 55 into active feeding position across the knitting needle path before the first needle to be employed for knitting the particular yarn or thread passes that point. This first needle, as aforesaid, may be the first needle of that portion of the needles along the cylinder circumference used for 60 knitting the reinforcement portion of the hose.

In accordance with the preferred operation of the invention, the first needle of said portion of needles will be actuated for knitting by the cam means directly adjacent the position of thread guide 8, while the thread end extending therefrom to the extension piece 2 will be carried along by said first needle to a point adjacent the location of thread separator 5, whereby severing of this thread end will occur close to the first stitch. In this manner, 70 the thread end held by the thread clamping device will be brought into contact with thread separator 5 cutting off such thread end and allowing the same to be retained by suction nozzle member 1 until extension piece 2 is next raised. The other end of the thread in the course being 75 knitted will be desirably short in length so that a minimum

of thread ends will occur in the knitting of the reinforcement portion.

In turn, when the last needle passes thread guide 8 in the direction of the arrow P, the control of thread guide 8 is such that the same will be upwardly displaced out of active feeding position. Nevertheless, the last knitting needle will carry the thread F along the path of movement of such needle a certain distance whereupon a similar pattern device such as a pattern drum will have caused draw rod 7 to be upwardly displaced also displacing extending piece 2. The already cut thread end will now pass through nozzle member 1. The thread F will pass directly beneath extension piece 2 as it is carried by the last needle toward thread separator 5. After a suitable movement of upward displacement, extension piece 2 will have been once again downwardly urged by draw-rod 7 in consequence of the control means used, i.e. a pattern drum or the like. The thread continues to move with the last needle until the same abuts the thread cutter or separator 5 whereupon the thread is cut at the terminal edge of the reinforcement portion of the hose such that the reinforcement portion terminal edge will have very short thread ends in consequence thereof. Since the remaining end of thread F is sufficiently long, the same will be readily retained by 2 even when said extension piece is next raised, due to the air suction through suction nozzle member 1.

Of course, alternatively, extension piece 2 may be kept in raised position until after thread F has been severed by separator 5 so that the thread end extending from thread guide 8 will be drawn by suction into nozzle member 1 and retained thereat in raised position as well as in extended position of member 2 into contact with dial cap 6.

Normally, extension piece 2 is raised once during each revolution of the cylinder since this is only needed to permit the thread to be clamped at the end of the knitting of a course of the reinforcement portion of the hose. Even so, the extension piece 2 may be raised after the start of the knitting of the next level or course of stitches of the reinforcement portion upon the severing of the portion of thread held by the clamping means from the new thread to be knitted, so that the thread end severed by thread separator 5 may be withdrawn through suction nozzle member 1. Of course, such removal may await the aforesaid raising of extension piece 2 at the cutting of the thread at the end of reinforcement portion whereby the already cut piece may be withdrawn through suction nozzle member 1 at that time.

With respect to FIGURE 2, a conventional straight bar knitting machine is shown having a bed of needles N and a cooperating bed of sinkers S along the center bed 15. A thread guide 8' is disposed in the conventional manner for passage along the needles and sinkers for the usual knitting procedure. At the end of the machine, when a particular knitting operation has been completed with respect to thread guide 8', the thread F is normally severed by a cutting or separating element 5'. In accordance with the present invention a suction nozzle means 1' is disposed directly adjacent the path of movement of the thread F carried by thread guide 8' along the course of the sinker head 14. In this instance, a lever 9 is disposed on a pivotable shaft 13, said lever having a cover plate 12 provided with a suitable elastic covering 11 formed of rubber or the like. Also disposed on shaft 13 is the conventional cutting element 5', which may take the form of an electrical resistance element which is heated to a high enough temperature to effect the severing of the thread or yarn F. While both lever 9 and thread separator or cutting element 5' are disposed for movement on a common shaft 13, cover plate 12 will be positioned with respect to said shaft at a point closer to the path of thread F than that of separator element 5'.

In this manner, upon pivoting shaft 13 to the left or

counter-clockwise, as viewed in the drawing, cover plate 12 will clampingly engage thread F against the nozzle rim of suction nozzle means 1' before separator element 5' comes into contact with the thread.

5 A suitable control mechanism may be provided which may be timed to be actuated to pivot shaft 13 in the desired forward direction as shown by the arrows just after thread guide 8' which is being withdrawn from active knitting position has passed the nozzle 1' along the course of movement thereof with respect to the sinker head 14. Naturally, it is preferred to resiliently mount lever 9 on shaft 13 so that upon contact between the nozzle rim of suction nozzle 1' and cover plate 12, shaft 13 may be turned even further a certain increment to allow thread separator 5' to come into contact with the thread F. Upon the return movement of thread guide 8' back into active knitting position, a suitable control may urge shaft 13 in reverse direction so as to withdraw cover plate 12 and separator element 5' from the path of thread F. Nevertheless, cover plate 12 may be again placed in engagement with nozzle means 1' to seal off suction by forward movement of shaft 13 a certain increment so that thread guide 8' may proceed with the further knitting in opposite direction without the thread being severed by separator element 5'.

30 If desired, once the knitting in the opposite direction has started, suitable further forward actuation of shaft 13 may occur due to the resilient mounting of lever 9 upon shaft 13, so that separator element 5' is once more brought into contact with the end of thread F between the needle bar and the nozzle means 1'. In this manner, only short thread ends will remain along the edge of the fabric. When thread guide 8' completes a further knitting operation, it is once more passed in the return direction towards separator 5'. Shaft 13 may be suitably actuated to withdraw separator 5' and disengage cover plate 12 from the rim of nozzle means 1' whereby the passage of thread therealong is facilitated. The cycle may then be repeated.

35 Specifically, in operation, for example, when the production of the double edge or turned welt portion of the knitted article has been completed, and another thread guide is to be inserted into active thread feeding position, a control linkage including a conventional pattern drum arrangement or other conventional means (see U.S. Patents 2,844,016 and 2,863,310) may cause the withdrawing of thread guide 8' from active knitting position to the inactive position shown in FIGURE 2. The thread guide 8' will remain in the inactive position shown in FIGURE 2 until next actuated.

40 However, prior to the withdrawing of thread guide 8' to the position shown in FIGURE 2, shaft 13 is rotated an increment in clockwise direction so that cover plate 12 and separator element 5' will be rearwardly urged out of the path of thread guide 8', to the position shown in FIGURE 2. When thread guide 8' has reached inactive position, shaft 13 may be forwardly rotated, so that the thread F will be clamped by cover plate 12 and nozzle means 1' will be sealed. Upon further forward (counterclockwise) rotation of shaft 13, separator element 5' will sever the thread F close to the fabric edge. Cover plate 12 will retain the thread end extending from thread guide 8' thereto. When thread guide 8' is again to be placed in active knitting position, shaft 13 again rotates in clockwise direction, withdrawing cover plate 12 and separator element 5' from the thread path, and allowing the previously severed thread end extending from thread guide 8' to the nozzle means 1' to be drawn by suction into the nozzle means 1'. After thread guide 8' has passed thereby and become engaged once more in active knitting of thread F, shaft 13 may be conveniently rotated in counterclockwise direction again to cause the covering of nozzle means 1' by cover plate 12 and thereafter the severing of the thread between nozzle means 1' and the fabric edge by element 5'. The severed

end of thread held between nozzle means 1' and cover plate 12 will be drawn off by suction through nozzle means 1' the next time cover plate 12 is withdrawn from clamping contact. The cycle may then be repeated.

It will be appreciated that shaft 13 may be duly actuated in the desired sequence in dependence upon a control linkage to a pattern drum in the conventional manner (see U.S. Patents 2,844,016 and 2,863,310).

FIGURES 3 and 4 illustrate the modification wherein a thread engaging projection 16 comprising a wire loop having an inwardly directed arcuate portion is disposed on cover plate 12. Projection 16 will, therefore, engage the thread F by the inwardly arcuate portion and force the thread within nozzle means 1' when lever 9 is pivoted in forward direction with cover plate 12 being placed in clamping engagement with the nozzle end of nozzle means 1'. A suitable length of the thread F will, therefore, be drawn so as to ensure a retention of the thread end even when cover plate 12 is withdrawn from clamping engagement with the end of nozzle means 1. It will be appreciated in this connection that by means of the projection 16, a sufficiently long piece of thread may be provided as desired, even though the suction nozzle means and thread clamping device of the invention are placed immediately adjacent the thread cutting or separator element 5' because of the restricted space for maintaining these working elements.

In accordance with the present invention, it will be appreciated that where desired cover plate 12 may be formed instead as a ring to permit clamping yet allow the passage of suction air into and through the nozzle opening.

To more clearly illustrate the preferred manner and sequence of withdrawing and inserting the thread guide means from an inactive yarn feeding position where the yarn is in non-knitting position to an active yarn feeding position wherein the yarn is fed to the needles for knitting thereby, FIGURES 5 and 6 are included. These figures show the invention as applied to a circular knitting machine and indicates that the clamping means of the invention and the cutting means for the yarn or thread may advantageously both operate when the yarn feeding means or thread guide 8a is moved to inactive yarn feeding position, whereas when the thread guide 8a is moved to active yarn feeding position, the clamping means may remain closed while the cutting means alone will operate.

Accordingly, as shown in FIGURE 5, the cylinder needles N rotate with the cylinder in the direction of arrow P. When the last needle which should take the yarn of the thread guide 8a, i.e. the reinforcement portion of the hose, for example, has passed thread guide 8a, a suitable control coupled with the rotation of the cylinder, for example such as a pattern drum, causes movement of thread guide 8a towards the center axis of the rotating cylinder of the circular knitting machine. At about the same time, draw-rod 7 upwardly displaces extension piece 2 so that the last needle which engages a thread will carry the same therewith along the cylinder circumference in the direction of arrow P. This needle passes through positions N, N₁, N₂, N₃, N₄. The path of movement of the thread during this time is illustrated schematically in dotted line such that the thread will be disposed directly beneath extension piece 2 by the time the same comes into contact with the thread separator 5. Draw-rod 7 may now be suitably actuated to permit thread clamping engagement between stationary cover plate 6 and extension piece 2. Once the thread abuts separator 5, it will be severed leaving only a short thread end at the terminal edge of the reinforcement portion of the course being knitted. The other end will be suitably drawn by suction into extension piece 2 and retained by extension piece 2 and dial cap 6 until after the thread guide 8a has next been switched into active yarn feeding position and is again switched to inactive position. The cycle is then repeated, extension

piece 2 being raised, the previously severed thread-end being drawn off by suction through nozzle member 1, the new thread once more passing directly beneath extension piece 2, extension piece 2 being lowered again and the thread again severed by separator 5 as indicated in FIGURE 5.

The control of inward movement of thread guide 8a may be carried out by means of rod 8b operatively linked with a pattern drum as mentioned above such that with 10 each revolution of needle N, thread guide 8a will be inwardly displaced just as needle N travels therewith in the direction of arrow P. A similar pattern drum or other device may be used to lift extension piece 2 from normal engagement with cover plate 6 just as thread guide 8a is 15 inwardly displaced, but in this case only until the thread passes directly therebetween whereupon extension piece 2 will be allowed to be lowered once again into clamping engagement.

Concerning FIGURE 6, the initial needle of that portion 20 of needles on the cylinder used for the knitting of the reinforcement portion of the hose is designated needle N_a. This needle is actuated in the normal manner for knitting, but before the same has passed thread guide 8a, suitable control by means of said pattern drum, for example, 25 causes such thread guide 8a to be outwardly displaced away from the center of the cylinder. The thread thus passes the path of needle N_a whereupon the thread is carried with the initial needle in the direction of arrow P, executing the positions N_{1a}, N_{2a}, N_{3a}, N_{4a}. The position 30 of the thread in this connection is schematically designated by dotted line. The free end of the thread during this movement is retained by extension piece 2 which is normally urged in engagement with cover plate 6. When the thread touches the separator element 5, the thread end 35 is cut e.g. at the initial edge of the reinforcement portion of the hose such that this edge will have only very small thread ends due to the close positioning of the needles and the separator element. The knitting is carried out in the normal manner during this time. The separated end of thread will be simply drawn by suction into extension piece 2 and nozzle member 1 as soon as extension piece 2 is next raised. The actuation of rod 8b in reverse direction to displace thread guide 8a outwardly with respect to 40 the center of the cylinder as aforesaid is suitably controlled by the pattern drum. For example, this may operate at the same rate as the cylinder speed of rotation where a reinforcement thread is to be knitted along a portion of each knitting course of the main thread, so that each cycle of the cylinder and the drum coincide for the desired 45 control movements.

Of course, where the thread guide 8a and the extension piece 2 are assigned for use during the knitting of hose in the normal manner, the thread guide 8a will be switched at first into active yarn feeding position. The extension piece 2 will not be raised once during each cylinder rotation but instead will be normally disposed in clamping contact with dial cap 6 while the knitting of the main courses progresses, and correspondingly, the thread guide 8a will remain in active position throughout. When the 50 main thread used for this purpose is to be withdrawn from active knitting position at the termination of the knitting with this thread, then the thread guide 8a will be switched out of active position and extension piece 2 will be raised to permit the thread to pass therebeneath for 55 clamping. Thereafter, the thread may be conveniently severed by separator 5, the thread end drawn into nozzle member 1 and clamping once more effected.

It will be appreciated, therefore, that in the initiating 60 of the knitting of a thread in the ordinary case thread guide 8a will be moved into active yarn feeding position (FIGURE 6) and separator 5 will be energized although extension piece 2 will remain in clamping contact with dial cap 6, whereas in the terminating of the knitting 65 of the thread, not only will thread guide 8a be moved

back to inactive position (FIGURE 5) but also extension piece 2 will be raised for thread clamping prior to severing of the thread end by energized separator 5 at the terminal edge of the last-knitted course.

The artisan, of course, will be aware that when several knitting systems are carried out simultaneously using multiple knitting stations, a thread clamping device in accordance with the invention, accompanied by a suitable thread separator element and thread guide may also be used at each station as desired.

It should be noted that while the particular thread clamping device is assigned to a thread guide or yarn feed means 8 for the reinforcement thread F to be knitted into the tubular hose or other knitted goods along a particular portion thereof during each knitting course, the normal knitting of the hose will be simultaneously carried out at a knitting station other than that for knitting the aforesaid reinforcement portion. Suitable conventional needle activating cam means may be employed for the separate knitting of the main thread and the separate knitting of the reinforcement thread F, said cam means being assigned to their respective knitting stations for activating predetermined needles having correspondingly assigned butts. Of course, if desired the thread clamping device of the invention can also readily be assigned for operation at a knitting station with a main thread guide or yarn feed means for the knitting of the main thread of the hose, being operable with the conventional separator element to clamp and cut the main thread being knitted when the knitting operation with such thread is to be terminated, as more fully appears from the copending application filed simultaneously herewith, Serial No. 93,804, filed March 6, 1961, entitled: Thread Changing Apparatus.

What is claimed is:

1. In a straight bar knitting machine having knitting elements, yarn feeding means movable from an active yarn feeding position wherein yarn is fed to said knitting elements for knitting thereby to an inactive yarn feeding position wherein the yarn is in non-knitting position, and means for clamping and cutting said yarn when said yarn feeding means is inactive yarn feeding position and for releasing said yarn when said yarn feeding means is moved to active yarn feeding position, the improvement which comprises a combined yarn clamping and suction device including suction nozzle means and yarn engaging surface means arranged for relative movement from a position out of yarn clamping contact to a position into yarn clamping contact with one another when said yarn feeding means is moved to inactive yarn feeding position, said surface means being provided with yarn engaging projection means insertable into said suction nozzle means during the yarn clamping contact, said projection means being adapted to engage the yarn to be clamped and carry a portion thereof into said suction nozzle means therewith upon yarn clamping contact whereby to form a loop portion in the yarn.

2. In a straight bar knitting machine having knitting elements, yarn feeding means movable from an active

yarn feeding position wherein yarn is fed to said knitting elements for knitting thereby to an inactive yarn feeding position wherein the yarn is in non-knitting position, and means for clamping and cutting said yarn when said yarn feeding means is in active yarn feeding position and for releasing said yarn when said yarn feeding means is moved to active yarn feeding position, the improvement which comprises a combined yarn clamping and suction device including suction nozzle means and yarn engaging surface means arranged for relative movement from a position out of yarn clamping to a position into yarn clamping contact with one another when yarn feeding means is moved to inactive yarn feeding position, said yarn feeding means being positioned to move from active to inactive yarn feeding position along a path between said nozzle means and surface means when said nozzle means and surface means are in open position out of yarn clamping contact, whereby said feeding means passes across the nozzle opening of said nozzle means to permit the yarn to extend across such nozzle opening and be clamped thereat when said nozzle means and surface means are moved to closed position in clamping contact with one another, said yarn engaging surface means being a cover surface adapted to seal off said suction nozzle means when in yarn clamping contact therewith.

3. Improvement according to claim 2 wherein said cover surface is provided with an elastic portion disposed thereon for sealingly engaging said suction nozzle means while clamping yarn therebetween.

UNITED STATES PATENT OFFICE
CERTIFICATE OF CORRECTION

Patent No. 3,188,835

June 15, 1965

Werner Mayer et al.

It is hereby certified that error appears in the above numbered patent requiring correction and that the said Letters Patent should read as corrected below.

Column 9, line 40, for "indicates" read -- indicate --; column 11, line 26, for "opreation" read -- operation --; column 12, line 5, for "active" read -- inactive --; line 12, before "yarn" insert -- said --.

Signed and sealed this 21st day of December 1965.
